BOTTLE

Harold K. Knight, Knox, Pa., assignor to Knox
Glass Associates, Inc., Knox, Pa., a corporation
of Pennsylvania

Application November 5, 1951, Serial No. 17,287

Term of patent 7 years

(Cl. D58—6)

To all whom it may concern:

Be it known that I, Harold K. Knight, a citizen of the United States, residing at Knox, in the county of Clarion and State of Pennsylvania, have invented a new, original, and ornamental Design for Bottle, of which the following is a specification, reference being had to the accompanying drawing, forming part thereof, in which:

Figure 1 is a side elevational view of a bottle, showing my new design.

Figure 2 is an edge elevational view.

Figure 3 is a bottom plan view.

Figure 4 is a fragmental enlarged sectional view as observed in the plane of line 4—4 on Figure 1.

Figure 5 is a fragmental enlarged sectional

view as observed in the plane of line 5—5 on Figure 1.

I claim:

The ornamental design for a bottle, substantially as shown.

HAROLD K. KNIGHT.
